UNITED STATES PATENT OFFICE.

FRANK ALDRICH, OF DETROIT, MICHIGAN, ASSIGNOR OF ONE-HALF TO JOHN M. NICOL,
OF DETROIT, MICHIGAN.

GARBAGE-CONTAINER.

1,131,102.

Specification of Letters Patent.

Patented Mar. 9, 1915.

Application filed December 15, 1911. Serial No. 666,052.

To all whom it may concern:

Be it known that I, FRANK ALDRICH, a citizen of the United States of America, residing at Detroit, in the county of Wayne 5 and State of Michigan, have invented certain new and useful Improvements in Garbage-Containers, of which the following is a specification, reference being had therein to the accompanying drawings.

10 In storing garbage from houses for ready collection, it is advisable that it be so disposed that excess moisture be drained off and that it does not freeze in cold weather or heat and therefore ferment or become offensive in warm weather. It should be inaccessible to animals, and the receptacle containing it should be built to stand rough usage by the collector.

This invention relates to receptacles for 20 garbage and the like whereby means are provided for retaining refuse in such manner that it does not pollute surrounding objects and is not offensive, and whereby moisture is drained away from the garbage and 25 disinfectant readily applied if desired to sterilize it.

Another feature is an arrangement, whereby the receptacle, which is constructed to stand rough handling, is protected from 30 either hot or cold weather, and cannot be molested by animals.

The invention consists in the matters hereinafter set forth and more particularly pointed out in the appended claim.

35 In the drawings, Figure 1 is a view in vertical section of an assembled device embodying features of the invention; and Fig. 2 is a view in perspective of a vessel for containing garbage, removed from the outer casing.

40 As shown in the drawings, an upright, cylindrical casing 1 adapted to be embedded in the earth for the greater portion of its length, has an inner flange or shoulder 2 near its upper end, and a cover 3 with depending marginal flange 4 telescoping over the upper end of the casing, which extends a short distance above the ground. A layer 45 of sand or like easily drained material is placed in the lower open end of the casing. Preferably the casing is a drain tile or sewer pipe section, the flanged end being placed uppermost.

A vessel having a body 6 preferably of 50 non-corrodible metal is suspended by an

upper marginal flange 7 thereon on the shoulder 2 of the casing. The flange is reinforced by a metal ring 8 or the like. A handle 9 is attached to the vessel by bail-ears 10 so as to be folded down out of the 60 way of the cover 3. The bottom plate 11 of the vessel is provided with drain perforations 12. To keep the vessel from being dented when it is tilted over the side or end-board of a garbage wagon or the like, a frame 14 65 has out-turned ends 15 secured against the under-side of the flange 7 and extends down the sides and across the bottom of the vessel in a plane at substantially right angles to the plane of the bail-ears, so that it forms a shoe 70 on which the pail may rest when it is being emptied over the edge of a wagon-box or the like. A tray 16 filled with disinfectant indicated at 17 and provided with perforations 18 for drainage may be placed below 75 the vessel if desired.

As a result of the general arrangement shown, a garbage container is had that effectively prevents the escape of odors and cannot be readily molested by passing animals. As it is bedded in the ground, the 80 contents does not become frozen in winter or fermented by summer heat, and any surplus moisture drains off, so that the garbage is easily collected and disposed of.

Obviously, changes in the details of construction may be made without departing from the spirit of the invention and I do not limit myself to any particular form or arrangement of parts.

90 What I claim is:—

In a garbage receptacle, means forming an annular support, a thin sheet metal vessel, an external marginal flange around the mouth thereof, a rigid frame having a middle portion extending diametrically across the under side of the vessel bottom plate to which it is connected adjacent the wall of the vessel, and side portion that extend longitudinally up the outside of the vessel, a 100 pair of oppositely disposed outturned end portions on the frame that underlie the flange of said vessel, a reinforcing ring secured on the upper face of the vessel flange, and to the outturned end portions of the 105 frame, a pair of bail ears secured to diametrically opposed sides of the vessel that extend outwardly and upwardly past the flanged ring in a plane at substantially right angles to the plane of the frame, the out- 110

wardly extending portions of said ears co-operating with the end portions of the frame in providing a bearing for said vessel upon said annular support, and a bail connected 5 to said ears and adapted to fold down on the vessel below the upper surface of said support.

In testimony whereof I affix my signature in presence of two witnesses.

FRANK ALDRICH.
